SOLE FITTING MACHINE

Frederic E. Bertrand, Lynn, Mass., assignor to
 United Shoe Machinery Corporation, Borough
 of Flemington, N. J., a corporation of New
 Jersey

Application June 6, 1940, Serial No. 339,150

31 Claims. (Cl. 12—27)

This invention relates to improvements in sole-fitting machines and is illustrated herein as embodied in a channeling machine which is adapted to operate upon different types of sole members including insoles having shank extensions.

In the use of channeling machines, as is well understood by those skilled in the art, it is necessary for the operator manually and rapidly to turn or swing the sole when sharp corners are reached as, for example, the sole must be turned approximately 180° in its own plane as the toe of the sole reaches the cutting means in order that the cutting shall proceed properly around the toe. Furthermore, turning the sole of a sharply pointed-toe style is considerably more difficult than is the same operation on a broad-toe style because the turning radius is smaller in the pointed-toe sole with the result that there is less room in which to make the turn.

It is an object of this invention to provide improvements in sole-fitting machines which will make it easier for operators to turn or swing soles about sharp corners. To this end, the illustrated machine, which is equipped with a pair of knives arranged to operate on the marginal portion of a sole, is provided with means which can be adjusted during the operation of the machine to shorten the stroke of the knives when the operation approaches a sharp corner, and, in addition, the machine is provided with further means which is arranged to slow down the speed of the knives when their stroke is shortened. This construction makes it easier to turn the sole and also retards the speed of the feed which is desirable when operating around corners. The controls for the above-mentioned means are both connected to a treadle so that when the operation approaches a corner, the operator can shorten the stroke of the knives, reduce the rapidity of their movement, and retard the speed of the feed by operating the treadle with his foot, and at the same time he can use both hands to swing the sole about the point of operation.

Further to facilitate turning of the sole, and in accordance with another feature of this invention, means are provided for disengaging the feed device from the sole member during a substantial part of each operating cycle. As illustrated, this means comprises a cam which moves the feed device heightwise from the sole member at the end of each cutting stroke and holds it away from the work for a substantial period during each operating cycle so as to give the operator ample opportunity to adjust the posi-

tion of the sole between the successive cutting strokes.

Heretofore, when it was desired to channel an insole having an extension such, for example, as the wing or tab portion of an orthopedic insole and to chamfer or bevel the edge of the sole at the lower or grain side, it was necessary to perform two separate machine operations, i. e., channeling and beveling. This was due to the fact that beveling knives in machines heretofore available could not be moved out of the path of the relatively wide sole extension on this type of insole during the operation of the machine and hence would gouge the under or grain surface of the extension if a channeling operation were carried out in the portion of the sole contiguous to the extension.

With this in view, it is another object of the invention to provide an improved sole-fitting machine which is capable of simultaneously channeling and beveling the marginal portion of an orthopedic insole and thus accomplishing in one machine operation results which have heretofore required two separate operations. To this end, another feature of this invention consists in the provision of mounting means for the chamfering knife which is so arranged that the chamfering knife can readily be moved below the surface of the work table during the operation of the machine and thus permit the sole extension to pass over the chamfering knife without being cut thereby and the channeling operation to progress through the portion of the sole contiguous to the extension. In accordance with another aspect of this feature of the invention, means are provided for interconnecting the edge gage and the chamfering knife so that the edge gage can be moved out of the path of the sole extension at the same time the chamfering knife is moved below the surface of the work table. As illustrated, the interconnected edge gage and chamfering knife are mounted on the work table carrier which is arranged to adjust them transversely to the line of feed through a normal range of adjustment and, when an extension of the sole is encountered, to move them to a predetermined position where an abutment acting on the interconnecting means causes the edge gage and the chamfering knife to move heightwise of the surface of the work table to a position where they are out of the path of the sole extension.

It has been found that in sole-fitting machines where the knives and the feed devices move in radial paths, the feed of the work is

accompanied by "twitching" produced by the alternate opposing action of the knives and the feed devices, which tend, first, to swing the sole edge against the edge gage and, then, to swing it away from the edge gage. While the "twitching" does not affect the channeling operation, it causes the chamfering knife to form a surface having a saw-toothed appearance due to the fact that the knife alternately cuts into and out of the sole edge.

With this in mind, it is another object of the invention to provide further improvements in sole-fitting machines, which will overcome "twitching" of the sole as it is fed past the chamfering knife and thereby improve the appearance of the beveling cut made by that knife. This object is attained by mounting one of the tool-supporting members for straight-line movement, and the other tool-supporting member for radial movement. In accordance with a preferred arrangement, the outer or edge knife and the inner or channeling knife are mounted on the straight-line tool-supporting member, and a feed device is mounted on the radially movable member. Movement of the channel knife in a straight line practically eliminates the throw of the work against the edge gage, while the sole-gripping action of both of the knives largely prevents the feeding forces from moving the sole away from the edge gage.

Invention is also to be recognized in the driving mechanism for oppositely moving the radial and the straight-line tool-supporting members, and in the simple and efficient control system for raising and lowering the work-feed device in timed relation to the movement of the tool carriers.

With the above and other objects in view, the invention will now be described with reference to the accompanying drawings, and will be pointed out in the appended claims.

In the drawings,

Fig. 1 is a perspective view of a machine head embodying the present invention;

Fig. 2 is a sectional view, taken through the head of the machine substantially on line II--II of Fig. 1, and showing the construction of the tool carriers;

Fig. 3 is an elevational view, partly broken away, of the mechanism at the height of the work table, the view being taken from the right side of the machine head as seen in Fig. 1 and showing particularly the edge gage and the chamfer knife in their out-of-the-way position assumed when the machine is operating on the tab portion of an orthopedic insole, and showing also the clutch control for the vertical drive shaft;

Fig. 4 is an enlarged exploded view showing the construction of the knife assembly;

Fig. 5 is an enlarged view, partly in section, showing the relation of the cam, cam strap, and tool-carrier operating lever;

Fig. 6 is an elevational view of a portion of the mechanism adjacent to the work table, the view being taken from the same viewpoint as Fig. 3 and showing the normal operating positions of the edge gage and the chamfer knife; and

Fig. 7 is a sectional view taken on line VII--VII of Fig. 6.

The machine shown in the drawings is of the type illustrated in Letters Patent of the United States No. 2,015,064, granted September 24, 1935 upon application of F. E. Bertrand, and comprises a head 10 in which is mounted a freely

rotatable work table 12 which is mounted on an adjustable carrier 13. Adjacent to one side of the work table is a chamfering knife 14 (Fig. 3) which is also supported on the carrier, while above the work table is an inner tool carrier 16, and an outer tool carrier 18. The elements just mentioned correspond respectively to those indicated by the numerals 74, 40, 420, 62 and 64 in the above-mentioned patent to Bertrand.

The inner tool carrier 16 (Fig. 2) is mounted for straight line movement by means of a pair of plates 20, 22 which are fastened to the tool carrier by screws 24 and engage respectively the opposite undercut sides of a dovetailed guideway 26 formed on the inside of the end wall 27 of the head 10. A tool slide 28 is mounted for vertical movement in a slideway 30 within the tool carrier 16. The slide 28 is adapted to yield upwardly against the action of a coil spring 32 which is housed within a bore in the upper part of the slide, the upper end of the spring bearing against a follower 34 which is engaged by an adjustable screw 36 threaded in a collar 38 clamped to a pin 40 which, in turn, is fastened to the upper plate 20. Downward movement of the knife slide 28 under the influence of the spring 32 is limited by a crossbar 42 which corresponds to the crossbar 236 in the machine disclosed in the above-mentioned Bertrand patent.

The outer tool carrier 18 (Fig. 2) is located opposite to the straight line carrier 16 and is provided with laterally extending heightwise spaced arms 44, 46 which extend over the top and bottom surfaces of a shoulder 48 formed on the head 10. The carrier 18 is pivoted to the shoulder 48 by a hollow sleeve 50 which extends through aligned openings in the arm 44, the shoulder 48 and the arm 46, the sleeve being attached to the arms by means of pins 52. The axis of the pivot sleeve is vertical and normal to the plane of a sole on the sole support 12, and oscillatory movement about this axis will not therefore include up-and-down components relatively to the sole. A second slide 54 consisting of a spindle 56 and a sleeve 58 is mounted for vertical movement in a slideway 60 within the carrier 18. A feed foot 82 is carried by the lower end of the spindle 56.

The sleeve 58 is formed with a counterbored recess for receiving a coil spring 62 which encircles the spindle 56, the lower end of the spring engaging a washer 64 seated against a shoulder on the spindle, while the upper end of the spring is seated against the top of the counterbored recess in the sleeve. The force of the spring 62 tends to urge the spindle downwardly relatively to the sleeve 58 and maintain the spindle in a vertical position determined by the engagement of a crosspin 66 in the spindle with the lower end of a vertical groove 68 in the sleeve 58. The spring will be compressed by continued downward movement of the sleeve after the tool carried by the spindle 56 has engaged the work on the table 12, thus adapting the tool carrier spindle to accommodate soles of different thicknesses.

The sleeve 58 is provided with an ear 70 which is connected to a swinging lever 72 by a link 74, the lever being mounted on a transverse cross-shaft 76 which is carried by spaced uprights 78, 80 (Fig. 1). As the tool carrier 18 moves the sleeve 58 laterally with respect to the path of movement of the lever 72, ball-and-socket joints are used to form the connections between the ear 70, the link 74 and the lever 72, these joints preferably being of the type shown in the United

States Letters Patent No. 2,173,155, granted September 19, 1939 upon an application filed in the name of F. E. Bertrand.

In the illustrated form of my invention, the channeling knife 150 (Fig. 4), the edge knife 152, and the presser gage 154 are all fastened to the knife slide 28 on the tool carrier 16. The means for fastening the channeling knife to the slide consists of a screw 156 which passes through an opening 158 in a knife block 160 and then into threaded engagement with the channeling knife. The block 160 is secured to a knife-block holder 162 by a screw 164 which passes through a horizontal elongated opening 166 in the block holder and then into threaded engagement with a tapped hole 168 in the knife-block 160; the elongated opening 166 permitting lateral adjustment of the channeling knife. The knife-block holder 162 is clamped to the slide 28 by a quickly releasable connection consisting of a slotted cap plate 170 which fits around the head of a screw 172 that passes through a second elongated opening 174 in the block holder 162 and then into threaded engagement with an opening 176 in the tool carrier. The elongated opening 174 extends in a vertical direction, making it possible to adjust the channel knife in a heightwise direction. When the knife-block holder 162 has been moved to a desired heightwise position and clamped against the tool slide, the screw 172 is held 30 against rotation by a clamp screw 178. To release the knife-block holder 162, the cap plate 170 is rotated in a counterclockwise direction a short distance to loosen the screw 172 and the cap plate is slid out from under the head of the screw, thus loosening the screw so that it can be backed off by hand if desired.

The edge knife 152 is mounted on a knife block 180 which is fastened to one end of a bracket 182 by a screw 184 which extends through an elongated vertical opening 185 in the block 180. The bracket 182 extends laterally from the slide 28, and is connected thereto by a screw 186. The screw 184 is provided with a slotted cap plate 188 which functions in the same manner as the cap plate 170 and, in addition, the screw is locked in its tightened position by a clamping screw 181. The presser gage 154 is fastened to a notched portion of the lower end of the tool slide 28 by a screw 192 (Figs. 3 and 4). The presser gage extends parallel to the bracket 182 and is provided with a pair of spaced downwardly extending presser feet 194, 196 which are located a slight distance in advance of the channeling knife 150 and the edge knife 152.

The tool carriers 16, 18 are oppositely moved back and forth by a lever 86 (Figs. 1 and 5) having a depending spindle 88 which is pivoted in a bearing 89 on the top of the head 10. The lever 86 is connected to a crank arm 90 on the outer tool carrier 18 by a link 92, and to the hinge joint 96 of a toggle which operates the slide 16 by a second link 94. The toggle consists of an arm 98 pivoted on a post 99 extending upwardly from the head 10, and a link 100 connected at one end to the pin 40 on the upper plate 20, the arm 98, link 100 and link 94 being connected together at the hinge joint 96. Thus, when the lever 86 is moved in a counterclockwise direction, as viewed in Fig. 1, the crank arm 90 is rotated in a counterclockwise direction, causing the tool carrier 18 to move rearwardly, and at the same time the arm 98 is also moved in a counterclockwise direction moving the hinge joint 96 for-

wardly and causing the tool carriage 16 to move forwardly.

The link 92 is connected to the lever 86 by a slide 102 (Fig. 1) which is mounted in a groove 104 formed in the top of the lever, and the extent of movement of the tool carriers is varied by adjusting the slide in the groove relatively to the axis of oscillation of the lever. The adjustment of the slide 102 is effected by the operation of a lever 106 which is connected to the link 92 by an adjustable link 108, the lever being operated by a rockshaft 110 which extends rearwardly beyond the head 10 to a point where it is connected with a treadle (not shown) by means of a rod 112 (Fig. 3). The rockshaft 110, rod 112, and the treadle (not shown) correspond respectively to the members 648, 656 and 658 in the patent to Bertrand No. 2,015,064.

The lever 86 is oscillated back and forth by a three-motion cam 114 (Fig. 5) which is surrounded by a cam-follower housing 116 that is moved back and forth by the cam, the housing 116 being connected to the lever 86 by a pin 118 (Figs. 1 and 5) which is fastened to an upstanding arm 120 on the rear end of the lever 86. The cam 114 is mounted on the upper end of a vertical drive shaft 122 which corresponds to the drive shaft 70 in the before-mentioned Bertrand Patent No. 2,015,064.

The cam 114 (Fig. 5) consists of a segment 124 of uniform radius, a segment 126 of decreasing radius, a third segment 128 of uniform radius, this radius being less than that of the segment 124, and a fourth segment 130 of increasing radius. When the cam is rotated in a clockwise direction from the position shown in Fig. 5, the segment 126 causes the lever 86 to move in a counterclockwise direction and the knives 150, 152 on the one hand and the feed foot 82 on the other hand to move toward each other on a cutting stroke. At the end of this movement, the segment 124 causes a dwell or suspension in the movements of the tool carriers, after which the segment 130 causes the tool carriers to reverse their motion and move the knives and the feed foot back to their starting positions; and, when they reach those positions, the segment 128 will cause a second dwell. As the cam 114 rotates, it acts on wear plates 132, 134, which are mounted in the cam follower 116, and is lubricated by wicks 136 that are mounted in oil pockets formed in the cam follower.

The arrangement described above substantially eliminates the before-mentioned "twitching" which heretofore accompanied the work feed and makes it possible for the chamfering knife to form a smooth, beveled surface. This is due to the fact that movement of the channeling knife in a straight line practically eliminates the throw of the work against the edge gage, while the gripping action of the knives 150, 152 and the presser feet 194, 196 on the work largely prevents the action of the feed foot 82 from moving the sole edge away from the edge gage.

The heightwise movement of the feed foot 82 is controlled by a pin 138 which extends upwardly from the cam 114 and is located eccentrically to the underlying drive shaft 122 (Fig. 5), the eccentric pin being connected by a link 140 (Fig. 1) to the swinging lever 72 which raises and lowers the feed foot. The eccentric pin is so located with respect to the control surfaces of the cam 114 that the pin lifts the feed foot from the work during the dwell which follows the feed stroke and holds the feed foot away

from the work throughout the return movement of the tool carriers and well into the dwell which follows this return movement. Thus it will be seen that during each operating cycle of the machine which is caused by the rotation of the drive shaft 122, the feed foot is disengaged from the work for approximately three-fourths of the operating cycle, giving the operator ample time to adjust the position of the work between each cutting stroke.

When the operation approaches a sharp corner, the operator customarily shifts the block 102 closer to the fulcrum of the lever 84, thereby reducing the amplitude of the oscillations imparted to the tool carriers 16 and 18, shortening the stroke of the knives, and reducing somewhat the speed of the feed. The speed of the feed in the illustrated machine is further reduced at this time by reducing the frequency of the oscillations of the tool carriers, this result being obtained by making the vertical drive shaft 122 in two sections (Fig. 3) and connecting those sections by a friction-type slip clutch 142. The lower element of the clutch 142 is provided with a sleeve 143 which is slidably mounted on the lower section of the drive shaft 122 and has a peripheral groove in which are seated shifting pins 144.

The controls for the block 102 and the clutch 142 are interconnected by means which will now be described, so that the speed of the upper section of the shaft 122, to which the cam 114 is connected, will progressively be reduced as the block is moved closer to the fulcrum of the lever 86. To this end the shifting pins 144 are connected to a forked lever 145 (Figs. 1 and 3) which is in turn connected at 147 to the treadle operated rod 112 which controls the shaft 110 and through it the block 102. Thus, by depressing the treadle (not shown), the elements of the slip clutch 142 will be moved apart as the stroke of the tool carrier is shortened, thereby causing a slow-down in the frequency of their back and forth movements.

The chamfering knife 14 is mounted on a knife carrier 200 (Figs. 3 and 6) which is pivoted on a lug 202 that projects upwardly from a flat lever 204, the lug being located beneath the edge of the work table 12. The lever 204 rests on the top of the work table carrier 13 and is swingably connected at its left end (Fig. 3) to a stud 206 which projects upwardly from the carrier 13. The opposite end of the lever 204 is attached to the lower portion of a post 208 that extends through a slot 211 (Fig. 7) in the forward end of an edge gage supporting member 210 and has its upper portion connected to an auxiliary work-supporting table 209 so that the auxiliary table moves with the lever. The lever 204 is connected to the member 210 by a pin 207 which extends through aligned openings in the lever and the member. The edge gage supporting member 210 is rectangular in shape and has an arm 212 which extends upwardly from its rear, or the right portion of the member as viewed in Fig. 6, the upper end of the arm being provided with a lateral extending pivot pin 214 upon which an edge gage 216 is mounted.

The edge gage 216 and the chamfering knife 14 are oscillated back and forth by a rocker member 218 which is provided with a pair of spaced arms 220 (Fig. 7) which slidably engage the opposite sides of the edge gage supporting member 210, thereby causing the member 210 to oscillate with the rocker member 218 while per-

mitting relative sliding horizontal movement between the members as required to permit inward and outward adjustment of the work table carrier 13 and the edge gage 216. The rocker member 218 is pivoted on the head 10 by a post 222 (Fig. 2) which is fastened at its lower end to the rocker member and extends upwardly into the opening in the sleeve 50 which also forms the pivot for the tool carrier 18. Movement of the tool carrier is transmitted to the rocker member 218 by means of a flat plate 224 which projects downwardly from the lower arm 46 on the tool carrier 18 into a slot 226 in the upper part of the rocker member. With the arrangement just described, the oscillating movements of the tool carrier 18 will be transmitted by the plate 224 to the rocker member 218 and to the member 210 which moves in unison with the rocker member. The member 210, in turn, transmits the oscillating movement through the pin 207 to the flat lever 204 which is caused to swing back and forth about the stud 206. As chips are cut from a sole edge by the chamfering knife 14 they are carried away from the work table by a chute 227 (Figs. 1 and 6) which is attached to the chamfer knife carrier 200. From the chute 227 the chips pass through a second chute 228 fastened to the work table carrier 13 by bolts 229 (Fig. 1).

30 The chamfering knife and the edge gage are adjusted back and forth relatively to the channelling and edge knives 150, 152 by the back-and-forth movement of the work-table carrier 13 which is controlled in the usual manner by 35 a hand lever 225 (Fig. 7) which corresponds to the hand lever 508 in the Bertrand Patent No. 2,015,064.

30 The chamfering knife and the edge gage 40 are arranged for heightwise movement relative to the surface of the work table 12 so that they can be moved out of the path of an extension on an orthopedic insole. To this end, the edge gage 216 is provided with a downwardly extending arm 230 which is connected to an arm 45 232 extending downwardly from the chamfer knife carrier 200 by a link 234. The chamfering knife and the edge gage are maintained in their normal operative position by means of a coil spring 236 which is connected at one end to the 50 lower end of the chamfering-knife arm 232 and at its other end to a pin 238 which projects out from the mid-portion of the edge-gage arm 230.

55 The edge gage and the chamfering knife will remain in their normal operative position shown in Fig. 6 while the work-table carrier 13 is adjusted back and forth to produce the usual variations in the width of the feather about the periphery of an insole. When, however, an insole extension is encountered, the work table carrier is moved to the right, as viewed in Figs. 3 and 6, an additional distance, causing an abutment 240 on the edge-gage arm 230 to strike the end of an abutment screw 242 mounted on the rocker member 218. This causes the edge gage 60 arm 230 to rotate in a clockwise direction, lifting the edge gage 216 above the surface of the work, and at the same time, the displacement of the arm 230 moves the link 234 to the left, as viewed in Figs. 3 and 6, thereby causing the 65 chamfer knife arm 232 also to rotate in a clockwise direction and move the chamfering knife 14 below the surface of the work support, as shown in Fig. 3.

70 Clockwise rotation of the chamfering-knife arm 232 and the edge-gage arm 230 causes an 75

appreciable stretch in the spring 236 so that when the work-table carrier 13 is again moved to the left sufficiently to carry the abutment 240 away from the screw 242, the action of the spring on the end of the chamfer-knife arm will cause that arm to move in a counterclockwise direction until it returns the chamfering knife to the position shown in Fig. 6. This movement of the arm 232 will cause a corresponding displacement of the link 234 which will move the edge gage down to its operative position. The return movement of the chamfering knife and the edge gage will be stopped when the edge gage strikes the auxiliary work table 209. It will be noticed that the line of action of the spring 236 passes closer to the pivot 214 of the edge-gage arm 230 than it does to the pivot 203 of the chamfering-knife arm 232 so that the action of the spring will cause the movement of the chamfering knife and the edge gage to their operative positions in the manner just described.

The work table 12 is raised and lowered by a mechanism similar to that disclosed in the Bertrant Patent No. 2,015,064, and in order to make sure that the rocker member 218 follows the downward movement of the work-table carrier, the post 222 (Fig. 2) which is fastened to the rocker member 218, is urged downwardly by a coil spring 244 which is housed within the sleeve 50. The lower end of the spring abuts the top of the member 222 while the upper end of the spring bears against a follower 245 which is engaged by an adjustable screw 248 threaded in an overhanging member 250 fastened to the tool carrier 18.

The operation of the machine will now be described. After the channeling knife and the edge knife are mounted on the knife carrier (Fig. 4), the machine is started and a sole is introduced into the machine in the usual manner. As the operation approaches a sharp corner, the operator depresses the treadle (not shown) moving the link 112 (Fig. 3) downwardly. This movement of the link causes the shaft 110 to rotate in a clockwise direction, as viewed in Fig. 1, moving the lever 106 with it. The movement of the lever 106 causes a corresponding movement of the links 108 and 92, which causes the block 102 to move in the slot 104 toward the fulcrum point of the lever 86 thereby reducing the amplitude of the oscillations imparted to the tool carriers 16 and 18. At the same time, the downward movement of the link 112 causes the clutch arm 145 (Fig. 3) to move downwardly and separate the clutch elements, allowing them to slip relatively to each other and causing the machine to slow down. After the operation progresses around the corner, the operator releases the treadle and the machine resumes its normal operation.

As the operation progresses around the periphery of the sole, the operator moves the handle 225 back and forth to vary the width of the feather in a desired manner. If the sole being operated upon is of the orthopedic type provided with an extension, the operator moves the handle 225 to a predetermined position when the point of operation reaches the extension. This moves the work-table carrier 13 an additional distance to the right, as viewed in Fig. 3, causing the abutment screw 242 to strike the abutment 240 and move the edge-gage arm 230 in a clockwise direction. Movement of the arm in this direction lifts the edge gage 216 above the insole extension and also displaces the link 234

to the left, causing the chamfering-knife carrier to move in a clockwise direction so as to lower the chamfering knife 14 below the surface of the work table. When the point of operation passes beyond the extension, the handle 225 is moved back to one of its feather determining positions thereby causing the work-table carrier 13 to move to the left and the edge-gage arm 230 to move away from the abutment screw 242. When the arm 230 moves away from this screw, the spring 236 moves the edge gage 216 and the chamfering knife 14 back to their normal operating positions, shown in Fig. 6.

Attention is herein called to United States Letters Patent No. 2,179,490, granted November 14, 1939, upon the application of William R. Bolton, and No. 2,216,153, granted October 1, 1940, upon the application of Frederic E. Bertrand, which disclose and which claim broadly an edge gage adjusting mechanism arranged to move an edge gage to an out-of-the-way position, thereby enabling the machine to operate conveniently upon orthopedic insoles having wing shank extensions.

Having thus described my invention, what I claim as new and desire to secure by Letters Patent of the United States is:

1. A sole-fitting machine comprising oppositely disposed tool carriers, a sole support, and control means for said carriers arranged to oscillate one of the tool carriers about an axis substantially normal to the plane of a sole on said support and to move the other tool carrier back and forth with a straight line motion.
2. A sole-fitting machine comprising a sole support, a tool carrier mounted for oscillatory movement about an axis substantially normal to the plane of a sole on said support, a second tool carrier mounted for straight-line motion, and operating means for simultaneously actuating said tool carriers.
3. A sole-fitting machine comprising a tool carrier mounted for oscillatory movement, a second tool carrier mounted for straight-line motion, and operating means for simultaneously moving said carriers in opposite directions.
4. A sole-fitting machine comprising a tool carrier mounted for oscillatory movement, a second tool carrier mounted for straight-line motion, and operating means for simultaneously moving said carriers in opposite directions, the operating means including a toggle arranged to move the second tool carrier back and forth.
5. A sole-fitting machine comprising a pivoted tool carrier, a second tool carrier mounted for straight-line motion, and operating means for the tool carriers including a crank for oscillating the pivoted tool carrier back and forth and a toggle for moving the second tool carrier back and forth.
6. A sole-fitting machine comprising a pivoted tool carrier, a second tool carrier mounted for straight-line motion, and means for oppositely moving said tool carriers, said means comprising a cam-driven oscillating lever and a linkage system for connecting the oscillating lever to the tool carriers, the linkage system being constructed and arranged to oscillate the pivoted tool carrier and simultaneously to impart straight-line motion to the second tool carrier.

7. In a sole-fitting machine having a work support and an edge gage associated therewith, a tool carrier mounted for oscillatory movement about an axis substantially normal to the plane of a sole on said work support, an oppositely dis-

posed tool carrier mounted for straight-line motion, a work-feed device mounted on one of said carriers, and a knife support mounted on the other carrier.

8. In a sole-fitting machine having a work support and an edge gage associated therewith, a tool carrier mounted for oscillatory movement about an axis substantially normal to the plane of a sole on said work support, a work-feed device mounted on said carrier for engagement with a work piece on the support, a second tool carrier mounted for straight-line motion, and a knife support mounted on the second carrier for engagement with the work piece.

9. In a sole-fitting machine having a work support and an edge gage associated therewith, a tool carrier mounted for oscillatory movement, an oppositely disposed tool carrier mounted for straight-line motion, a work-feed device mounted on one of said carriers, and means for moving the work-feed device out of contact with the work, said means including a lever spaced heightwise with respect to the feed device and a link pivoted at one end to the lever and at the other end to the work-feed device.

10. In a cyclic-operated sole-fitting machine having a work support and an edge gage associated therewith, a tool carrier mounted for oscillatory movement, an oppositely disposed tool carrier mounted for straight-line motion, a work-feed device mounted on one of said carriers and a knife support on the other member, and means for disengaging the work-feed device from the work support during more than half of each cycle of the machine.

11. In a cyclic-operated sole-fitting machine, a tool carrier mounted for oscillatory movement, an oppositely disposed tool carrier mounted for straight-line motion, a work-feed device mounted on one of said carriers and a knife support on the other carrier, a cam arranged to move said carriers back and forth during each operating cycle, said cam being arranged to produce a dwell in the movement of the carriers at the end of the cutting stroke of the knife, and means associated with the cam and connected with the work-feed device arranged to disconnect the feed device from the work at the end of the cutting stroke and to hold it away from the work until the beginning of the next cutting stroke.

12. In a sole-fitting machine for operating upon sole members, the combination of a work support, a chamfering knife associated with the work support, a feed device carrier mounted for oscillatory movement about an axis substantially normal to the plane of a sole on said work support, a knife carrier mounted for straight-line movement, and means for operating said carriers.

13. In a sole-fitting machine for operating upon sole members, a work support, an oscillating chamfering knife associated with the work support, a feed-device carrier mounted for oscillatory movement, a knife carrier mounted for straight-line motion, sole-fitting knives attached to said knife carrier, and a presser gage associated with said knives.

14. In a sole-fitting machine having a tool carrier mounted for to-and-fro movement, adjustable operating means for the tool carrier, and means for adjusting the operating means to vary the extent of movement of the tool carrier and for varying the speed of the machine in a determined relation to the adjustment of the tool carrier.

15. In a sole-fitting machine having a tool car-

rier mounted for to-and-fro movement, adjustable operating means for the tool carrier, and means for adjusting the operating means during the operation of the machine to vary the extent of movement of the tool carrier and for reducing the speed of the machine as the extent of movement of the tool carrier is shortened.

16. In a sole-fitting machine having two oppositely disposed tool carriers mounted for to-and-fro movement, adjustable operating means for simultaneously moving the tool carriers in opposite directions, and means for adjusting the operating means to vary the extent of movement of the tool carriers and for varying the speed of the machine in a determined relation to the adjustment of the movement of the tool carriers.

17. In a sole-fitting machine having a tool carrier mounted for to-and-fro movement, adjustable operating means for the tool carrier, a control for adjusting the operating means during the operation of the machine to vary the extent of movement of the tool carrier, and a second control associated with the operating means for adjusting the speed of the machine in a determined relation with the adjustment of the movement of the tool carrier.

18. In a sole-fitting machine having a tool carrier mounted for to-and-fro movement, means including an adjustable operating arm and a slip clutch for operating the tool carrier, and means for adjusting the operating arm during the operation of the machine to vary the over-all movement of the tool carrier and for simultaneously regulating the amount of slip in the clutch in a determined relation to the over-all movement of the tool carrier.

19. In a sole-fitting machine having a tool carrier mounted for to-and-fro movement, means including an adjustable operating arm and a slip clutch for operating the tool carrier, and a treadle controlled linkage system connected with the adjustable arm and the slip clutch for simultaneously adjusting the over-all movement of the tool carrier and the amount of slip in the clutch.

20. In a sole-fitting machine having a tool carrier mounted for to-and-fro movement, an adjustable vibrating arm operatively connected with the tool carrier for moving said carrier to and fro, driving means including a slip clutch operatively connected with the vibrating arm, and means for adjusting the vibrating arm to vary the over-all movement of the tool carrier and for regulating the amount of slip in the clutch in a determined ratio to the over-all movement of the tool carrier.

21. In a sole-fitting machine adapted for operating upon sole members provided with extensions, a work support, sole-fitting means, a chamfering knife arranged to bevel the edge of a sole as it is operated upon by the sole-fitting means, and means for lowering the beveling knife below the surface of the work support when a portion of a sole having an extension thereon is reached thereby to enable the extension to pass over the beveling knife and the sole-fitting operation to continue in the portion of the sole which is contiguous to the extension.

22. In a sole-fitting machine adapted for operating upon sole members provided with extensions, a work support, an edge gage, a chamfering knife arranged to bevel the edge of a sole as it moves past the edge gage, and means for moving the edge gage and the chamfering knife out of the path of an extension on the sole member.

23. In a sole-fitting machine adapted for operating upon sole members provided with extensions, a work support, an edge gage, a chamfering knife arranged to bevel the edge of a sole as it moves past the edge gage, and means for moving the edge gage and the chamfering knife out of the path of an extension on a sole member, said means being arranged to raise the edge gage out of engagement with the sole member.

24. In a sole-fitting machine adapted for operating upon sole members provided with extensions, a work support, an edge gage, a chamfering knife arranged to bevel the edge of a sole as it moves past the edge gage, and means for moving the edge gage and the chamfering knife out of the path of an extension on a sole member, said means being arranged to lower the chamfering knife below the surface of the work support.

25. In a sole-fitting machine adapted for operating upon sole members provided with shank extensions, a work support, an edge gage arranged for movement in the plane of the work on the work support, a chamfering knife arranged to bevel the edge of a sole member as it moves over the work support, means for adjusting the edge gage through a predetermined range of movement, said means being arranged to move the edge gage and the work support out of the path of the work when it is moved beyond the predetermined range.

26. In a sole-fitting machine adapted for operating upon sole members provided with extensions, a work support, sole-fitting means, an edge gage for guiding a sole member past the sole-fitting means, a chamfering knife for operating on the edge of a sole member as it passes over the work support, means for adjusting the edge gage and the chamfering knife through a predetermined range of movement relatively to the sole-fitting means, and means for moving the edge gage and the chamfering knife heightwise relatively to the surface of the work support when they are moved beyond the predetermined range.

27. In a sole-fitting machine adapted for operating upon sole members provided with extensions, a work support, sole-fitting means, a support arranged for movement relatively to the sole-fitting means, an edge gage and a chamfering knife both adjustably mounted on said support, means for moving the support relatively to the sole-fitting means to adjust the edge gage across the line of feed, and means effective when the support is moved to a predetermined posi-

tion to move the edge gage and the chamfering knife out of engagement with a sole member on the work support.

28. In a sole-fitting machine adapted for operating upon sole members provided with extensions, an edge gage, a chamfering knife, means for interconnecting the edge gage and the chamfering knife, and means for operating the interconnecting means to move the edge gage and the chamfering knife heightwise away from the surface of the work support.

29. In a sole-fitting machine adapted for operating upon sole members provided with extensions, a work support, sole-fitting means, an edge gage adjustable relatively to the line of feed, a chamfering knife arranged to bevel the edge of a sole member provided with an extension as it moves over the work support, means for interconnecting the edge gage and the chamfering knife, and means for operating upon the interconnecting means when the operation reaches the extension to cause the edge gage to move above the surface of the work support and the chamfering knife to move below that surface thereby to permit the extension to pass between the edge gage and the chamfering knife.

30. In a sole-fitting machine adapted for operating upon sole members provided with extensions, a work support, an edge gage and a chamfering knife arranged for operative engagement with a sole member passing over the support, means for moving the edge gage and the chamfering knife heightwise with respect to the surface of the work support to permit the passage of the sole member extension, and resilient means arranged to urge the edge gage and the chamfering knife to their normal operative positions.

31. In a sole-fitting machine adapted for operating upon sole members provided with extensions, a work support, an edge gage mounted for movement upwardly from the surface of the work support, a chamfering knife mounted for movement heightwise through the plane of the surface of the work support, means for interconnecting the edge gage and the chamfering knife, a carrier for the edge gage and the chamfering knife mounted for movement transversely of the line of feed, and means arranged to operate upon the interconnecting means when the carrier is moved to a predetermined position to move the edge gage and the chamfering knife out of the path of an extension on a sole member.

FREDERIC E. BERTRAND.

CERTIFICATE OF CORRECTION.

Patent No. 2,265,338.

December 9, 1941.

FREDERIC E. BERTRAND.

It is hereby certified that error appears in the printed specification of the above numbered patent requiring correction as follows: Page 3, second column, line 1, for "carriage" read --carrier--; page 5, first column, line 24, for "Bertrant" read --Bertrand--; page 6, second column, line 44, claim 19, for "carried" read --carrier--; and that the said Letters Patent should be read with this correction therein that the same may conform to the record of the case in the Patent Office.

Signed and sealed this 3rd day of February, A. D. 1942.

(Seal)

Henry Van Arsdale,
Acting Commissioner of Patents.
